COUNTER AND NUMBERING HEAD FOR PRESS CYLINDERS

Oscar C. Roesen, Scarsdale, N. Y., assignor to
Wood Newspaper Machinery Corporation,
Plainfield, N. J., a corporation of Virginia

Application February 20, 1942, Serial No. 431,758

5 Claims. (Cl. 101—72)

The following specification relates to my invention in an interruptible revolution counter and numbering head for press cylinders. More specifically it is for giving consecutive numbering to the revolutions of press cylinders capable of being rendered inoperative by a momentary interruption on the event of the production of printing rendered defective by splicing of the paper webs.

It is usual practice to splice successive webs of paper as they are fed to a rotary press. The splicing operation may be by hand or automatic. It results in the production of a defective printed unit which must be discarded. The discarding of such a printed unit results in an error of the numbering machine by which the successive impressions of the rotary press are counted and marked. In the patent of H. A. W. Wood granted July 28, 1936, No. 2,048,765 a throw-out device has been disclosed in which the automatic pasting mechanism sets into motion mechanism which results in displacing askew the printed and folded unit containing the section of spliced paper.

One of the objects of my invention is to provide a numbering mechanism for use in conjunction with a throw-out device operating accurately to correct for the individual printed units discarded by reason of splicing defects.

A further object of my invention is to interrupt the normal operation of such a numbering device in response to abnormal conditions or events.

One of the objects of my invention is to safeguard the numbering machine from inadvertent and accidental interruption not connected with the occurrence of an event which it is desired to disregard in numbering.

A still further object of my invention is to provide equipment for the above purposes which will be adaptable to existing printing presses and which will be actuated by the operation of splicing webs in the normal operation of existing printing presses.

With a view to describing my invention I have shown the preferred form thereof in accompanying drawings in which

Fig. 1 is a side elevation of parts of a rotary printing press assembly showing my improved numbering head and means for interrupting its operation;

Fig. 2 is an end view of the same partly in vertical section;

Fig. 3 is a vertical cross-section on the line 3—3 of Fig. 2;

Fig. 4 is an elevation of the rotary operating wheel 55.

mechanism for interrupting the numbering device;

Fig. 5 is a plan view of the same;

Fig. 6 is a diagram of the electrical circuits used; and

Fig. 7 is a view of one form of splicer.

My invention is used in conjunction with a rotary printing press having a splicing means and a paper throw-out device such as is disclosed in the Wood Patent 2,048,765. The splicing mechanism shown in this Patent 2,048,765 is shown in the present case at Fig. 7, wherein the running web W and the web roll 100 are associated with a pasting device 110 which involves a solenoid 120 in an electric line. In series with this solenoid are a pair of contacts 130 which are adapted to be closed by a switch 140 operated by a cam 150 rotating with the web roll. The roll 100 after it gets into the proper position is started into rotation in the proper direction and once during each rotation the cam 150 closes the contacts 130 and 140. This occurs when the pasted spot on the roll 100 reaches the proper position for attachment to the web W. I have shown the pasting device in a form involving a brush 160 for finally bringing the parts together. Such a press includes the pasting or splicing mechanism diagrammatically indicated in Fig. 5, the printing and numbering mechanism, Fig. 1, and timing means for offsetting the defective printed sections, Figs. 2 and 3, as more clearly apparent from Fig. 4. To this mechanism, I have added a numbering mechanism by which the printed impressions are successively numbered and combined therewith appropriate means for interrupting the numbering device or rendering it inoperative so that the defective copies will be disregarded.

In my drawings I have shown a cylinder or rotary printing press of the usual construction having a frame 6. The cylinder 7 has opposed to it a plate cylinder 8. The web 9 travels vertically between the cylinders 7 and 8, each rotation of the latter representing a printed impression which it is desired to number, suitable provision also being made to disregard from the numbering any impression on a spliced section of the web 9.

The cylinder 8 has a reduced end 10 as shown in Fig. 2. Inwardly of the reduced end the cylinder 8 has a recess 11 in which a numbering machine 12 is appropriately journaled. This numbering machine is actuated by a shaft 14 rotatably journaled in the reduced end 10 of the cylinder 8 as shown in Fig. 2 and carrying star wheel 13.

The frame 6 has a bracket 16 which supports an electromagnet 17. The solenoid or plunger 18 of the electromagnet is held down by gravity and carries a pivoted link 19 from which is suspended a pawl 20. The pawl 20 is in the form of a lever which is pivoted as at 21 to the frame. A spiral spring 22 serves to hold the pawl in its lower position in the path of the star wheel 13. In this way the pawl actuates the star wheel once in every revolution of the cylinder 8 resulting in the successive numbering of the impressions on the web 9.

A throw-out mechanism such as is described in the Wood patent is provided as shown in Figs. 4 and 5. Here the frame standard 23 carries a journal 24 in which rotates a shaft 25. The rate of rotation is controlled by the operation of the printing press. The end of the shaft 25 is in the form of a spiral worm gear 26. A lower bracket 27 extends laterally from the standard 23 below the shaft 25. A companion bracket 28 extends laterally from the standard 23 above the shaft 25. Brackets 27 and 28 form journals for a shaft 29. Above the lower bracket 27 shaft 29 carries, keyed or otherwise attached, a worm wheel 30 in engagement with the worm gear 26.

Above the bracket 28 shaft 29 carries a friction disk 31. The upper end of the shaft 29 has a loose clutch or drum 32. This drum 32 is held down against the friction disk 31 by a spring 33, washer 34 and lock-nuts 35. This arrangement causes the drum 32 to rotate with the shaft 29 except when the friction between disk 31 and drum 32 is overcome.

A detent 36 is formed on the circumference of the drum 32. Opposite this detent there is an electromagnet 37 mounted on the upper bracket 28. The solenoid or plunger 38 of the magnet is provided with a latch 39 which may be urged outwardly into the path of the detent 36. The plunger 38 is biased for normal position to be positioned in the path of the detent 36.

The drum 32 carries a peripheral cam 40 suitably spaced with respect to the detent 36. Normally in the path of the rotation of the cam 40 there is a switch 41. This switch is open except when it is moved back by contact with the cam 40.

A second cam 42 is formed on the peripheral of the drum 32 and suitably spaced from the detent 36 and the first cam 40. Bracket 28 is extended to form a column 43 on which is mounted a normally open switch 44. This switch has a plunger 45 normally extending outwardly into the path of travel of the cam 42. As the cam 42 passes plunger 45 it closes switch 44.

In the order of their sequence, the latch 39 is withdrawn from detent 36 the moment the splice is made and drum 32 begins to turn, then cam 42 closes switch 44, energizing solenoid 17 which makes the numbering head inoperative. Then when the unnumbered copies arrive at the delivery, cam 40 closes switch 41 to make kicker 53 operative for setting the defective copies askew on the delivery.

Electromagnet 17 is provided with a holding or bridging switch 46 so that the circuit once closed through magnet 17 remains closed until interrupted. In order to interrupt this circuit I have provided a cam 47 on the shaft of cylinder 8. This cam 47 operates a circuit breaker 48 once every revolution. The switch breaker 48 and cam 47 are used to insure that the solenoid 17 can be energized only when the numbering device is not in actual operation. The length of

cam 42 determines how long solenoid 17 will remain energized.

Current is supplied through circuit 49 simultaneously with the formation of a splice by the usual pasting mechanism. This current flows through electromagnet 37 retracting the latch 39 and permitting the drum 32 to rotate by frictional engagement with the friction disk 31. This brings cam 40 past the switch 41 closing the circuit 50 to the signal 51 and magnet 52. The latter operates the kicker 53 to offset the defective printed copy which has by this time reached the delivery mechanism.

In appropriate time sequence the cam 42 closes the normally open switch 44. This energizes the electromagnet 17 which lifts its plunger 18 thus taking the latter out of the path of the star wheel 13. As the circuit breaker 48 is closed the current continues to flow through the solenoid 17 holding the latch 20 out of the path of the star wheel 13. However, the cam 47 operates to open the circuit breaker 48 once in every revolution.

Cam 47 opens the circuit breaker 48 for a brief interval, each revolution of cylinder 8 to prevent lifting of pawl 20 during the brief interval during which changing of the numbering mechanism takes place to prevent incomplete or partial operation of the numbering head.

Operation of the several details of this assembly has been indicated above. At the time when a splice is made solenoid 37 retracts the latch 39 permitting the cam drum to revolve with the friction disk 31 of shaft 29. The worm gearing is such as to bring cam 40 opposite switch 41 when the defective printed copy reaches the delivery machine. Thus the kick-out device 53 displaces the defective copy and the signal 51 is energized.

Further rotation of the cam drum 32 brings cam 42 in contact with switch 44. The circuit is then closed from line 50 through the magnet 17 and the latch on the pawl 20 retracted out of the path of the ratchet wheel 15. Since circuit breaker 48 is closed the latch remains retracted until cam 42 permits switch 44 to open and de-energize magnet 17. The length of cam 42 can be made to suit the length of web desired to pass through the press without being numbered. The pawl 20 then falls back into the path of the star wheel 13 and the numbering continues.

This arrangement provides for the normal operation of a numbering head without interruption until a splicing operation is performed. On the occurrence of splicing a web, the numbering head is rendered inoperative, and the defective copies are offset from their ultimate normal delivery. The interruption of the numbering sequence may precede the offsetting delivery operation. Thus the cams on drum 32 may be arranged in such an order that the interruption of the numbering will occur as the spliced portion of the web passes the numbering head and prior to the operation of the kicker when the spliced portion finally reaches the point of delivery.

The above description is of the preferred form but merely illustrative and various changes in arrangements, details and proportions may be made within the scope of the following claims.

What I claim is:

1. In combination with a rotary cylinder printing machine and associated delivery and web feeding mechanisms, splicing means for the webs, a numbering head on the cylinder, a ratchet wheel for the numbering head, a pivoted pawl on the machine frame in the path of the

ratchet wheel, an electro-magnet controlled by the splicing means for retracting the pawl from the path of the ratchet wheel, and a holding circuit for the electro-magnet operated by the electro-magnet, and a circuit breaker in the holding circuit.

2. In combination with a rotary cylinder printing machine and associated delivery and web-feeding mechanisms, splicing means for the webs, a numbering head on the cylinder, a ratchet wheel projecting beyond the end of the cylinder and actuating the numbering head, a pawl pivoted on the machine frame with its end lowered normally into the path of the ratchet wheel, a spring for holding the pawl in lowered position, a magnetic coil above the pawl, an armature therefor, a link between the armature and pawl and electrical circuits so connected as to actuate the coil in timed sequence after the operation of the splicing means.

3. In combination with a rotary cylinder printing machine and associated delivery and web-feeding mechanism, splicing means for the webs, a numbering head on the cylinder, a ratchet wheel projecting beyond the end of the cylinder and actuating the numbering head, a pawl pivoted on the machine frame with its end lowered normally into the path of the ratchet wheel, a spring for holding the pawl in lowered position, a magnetic coil above the pawl, an armature therefor, a link between the armature and pawl, an electrical circuit so connected as to actuate the coil in timed sequence after the operation of the splicing means and a holding circuit for the coil, and a circuit breaker in the holding circuit.

4. In combination with a rotary cylinder

printing machine and associated delivery and web-feeding mechanisms, splicing means for the webs, a numbering head on the cylinder, a ratchet wheel projecting beyond the end of the cylinder and actuating the numbering head, a pawl pivoted on the machine frame with its end lowered normally into the path of the ratchet wheel, a spring for holding the pawl in lowered position, a magnetic coil above the pawl, an armature therefor, a link between the armature and pawl, an electrical circuit so connected as to actuate the coil in timed sequence after the operation of the splicing means, a holding circuit for the coil, a circuit-breaker in the holding circuit, and a cam on the cylinder for periodically opening the circuit-breaker.

5. In combination with a rotary cylinder printing machine and associated delivery and web-feeding mechanisms, splicing means for the webs, a numbering head on the cylinder, a ratchet wheel for actuating the numbering head, a pawl on the machine frame with its end normally in the path of the ratchet wheel, an electro magnet for removing the pawl from said path, a shaft rotated by the machine, a friction disk on the shaft, a spring-held drum rotated by the disk, a detent on the drum, a cam on the drum angularly spaced from the detent, a magnetic coil mounted on the machine frame, an armature for the coil, a latch on the armature normally in engagement with the detent, a coil-operating circuit energized by the action of the splicing means to retract the latch from the detent, and a switch in the path of the cam for energizing said electromagnet.

OSCAR C. ROESEN.
